UNITED STATES PATENT OFFICE.

FRED H. MCCOY, OF BURLINGTON, VERMONT, ASSIGNOR TO MEAD MANUFACTURING COMPANY, OF BURLINGTON, VERMONT, A CORPORATION OF VERMONT.

COMBINED FOLDER FOR SEWING-MACHINES.

1,357,105.

Specification of Letters Patent. Patented Oct. 26, 1920.

Application filed March 20, 1917. Serial No. 156,188.

To all whom it may concern:

Be it known that I, FRED H. MCCOY, a citizen of the United States, residing at Burlington, in the county of Chittenden and 5 State of Vermont, have invented certain new and useful Improvements in Combined Folders for Sewing-Machines, of which the following is a specification.

This invention relates to an improvement 10 in sewing-machine attachments, and appertains more particularly to a device for producing artificial seams capable of use in connection with any feller.

One of the objects of the invention is to 15 provide a device which is readily attachable to any sewing-machine of standard type. Another object is to form an improved type of feller having attached thereto a seamer, whereby an ordinary lap seam can be formed 20 upon the feller without making any adjustments, and then, without substituting any additional parts, an artificial seam may be produced upon the upper part of the feller proper.

25 The utility of a device of this character will be apparent as the description proceeds, especially when applied to the manufacture of the so-called two seam overall and pant, where an artificial seam made on 30 the above combination feller and seamer would make a large saving in labor and material, over and above the present method of construction.

In the accompanying drawings forming 35 part of the specification,

Figure 1 is a perspective view of a machine with the attachment in place, showing in dotted lines the creaser-arm in its extended position;

40 Fig. 2 is a detail perspective view of the mounting for the creaser-arm;

Fig. 3 is a vertical cross-section through the improved feller disclosing a piece of goods in the act of being creased by the 45 creaser-arm;

Fig. 4 is a side elevation of the pivoted end of the creaser-arm disclosing in dotted lines the creaser-arm in its operative position;

50 Fig. 5 is a vertical cross-section taken on the line 5—5 of Fig. 4; and

Fig. 6 is a perspective view of goods which have been folded and sewed.

To the work support 1 is affixed the feller 2, 55 of the usual construction as regards the lower part thereof, but which carries the

felling member 3 on the upper side thereof. The feller 2 is located in the usual position in front of the two-needle sewing element 4 mounted in the frame 5. Detachably secured by a set-screw is a supporting member 7, which is slotted longitudinally as at 8. In one end of this slot is pivotally mounted the creaser-arm 9, as by the bolt 10.

Pivoted upon one end of the 65 supporting member 7 is a locking arm 11, provided with a cam 12 intermediate thereof. The arm 11 is bent at practically right-angles to form the handle 13. An arm 14^a extends from the flanged plate 14 rigidly 70 affixed to the supporting member 7 on the opposite side of the slot 8 from the arm 11. To the arm 14^a is affixed a spring 15 fastened to the arm 11 at 16.

The arm 9 in its inoperative position extends outwardly, as shown in dotted lines in Fig. 1. When it is desired to swing it into position, the operator gives it an inclination about its axis 10, and the bevel 17 on the inner end thereof will ride up upon 80 the cam 12, thus moving the arm 11 about its pivot 11^a against the action of the spring 15. As soon as the end forming the bevel 17 reaches the apex of the arm 12, the arm will spring back into position behind it, and the 85 cam 12 will act as a shoulder to prevent its movement. The flanged plate 14 is so adjusted as to be engaged by the arm 9 just as the inner end 17 drops off the cam 12, which will obviously hold the arm 9 in a rigid position incapable of movement in either direction until the arm 11 has been raised, thus removing the cam 12 as a stop, and permitting the arm 9 to be swung to its inoperative position.

90 The creaser-arm 9 carries a creaser 18 adapted to crease the goods 19 in the felling member 3, as indicated in Fig. 3.

95 The utility of the invention will be plain when it is remembered that at present it requires two different and distinct devices to do the work of this combination feller and seamer; in other words, this invention contemplates the use of one device to produce both real and artificial seams by the same 100 operator and same machine, saving time and expense. By the use of this combined folder, I am doing away with two separate machines and two operators and the necessary changing of work from one operator to 105 the other, all of which takes time, and, therefore, it is a real saving in both time and ex-

pense, which during the year is quite considerable. Without the combined folder, it is absolutely necessary to have two separate machines to perform the same work.

- 5 For instance, in the sewing of a bifurcated piece of goods, where there has been some part cut out, it will be obvious that the bifurcated portion of the goods may be joined and sewed by the lower portion of 10 the feller, and when the end of the bifurcation is reached, the work is stopped for an instant while the goods are raised out of the lower feller with a slight twist of the operator's hand, the arm 9 is swung into position, and the creaser 18 folds the goods from the end of the genuine seam to the end of the piece of goods, the appearance of the finished article not being marred by a seam running but a part way of its length, such as 15 20 25 30 35 40 45 50
- results from the use of machines now on the market. If the operator is making an artificial seam with the creaser arm in place on the feller member and she comes to the raw edges to be felled by the lower feller it is not even necessary to remove the creaser arm, as the cloth or material will drop into the lower feller and the work continue. There is a stoppage of the work only long enough for the operator to bring the two raw edges in place in the lower feller. This results in a great saving of time in the continuation of a real lap seam to an artificial seam, as it is not necessary that the work be removed from the combined folder in passing through one feller member after passing through the other. It is obvious, however, that it might be used for the production of any kind of artificial seam.

It is believed that the operation of the invention will be apparent. When the feller proper is to be used, the handle 13 is raised, and the operator is then able to swing the arm 9 about its pivot into its inoperative position, where it is out of the way, yet readily accessible; and, as soon as there is any demand for the use of the upper feller, it requires but a simple manual operation to swing the arm 9 into its operative position, where it is automatically locked and held.

The seam formed by the combined folder forms the subject matter of a divisional application filed August 30, 1920, Serial #406,743.

55 It is obvious that many changes might be made in the invention, without departing from the spirit thereof, hence it is not desired to limit to the precise construction disclosed, but:—

60 I claim:—

1. An attachment for sewing machines comprising a feller for forming a real lap seam, a feller member connected thereto, and means coöperating with said feller member for forming an artificial lap seam,

said feller and feller member converging toward a common delivery point.

2. As an article of manufacture a combined folder for sewing machines comprising a lap seam forming feller having wings 70 for folding material, one of the wings terminating in a felling member, and means adapted to coöperate with said felling member for forming artificial lap seams.

3. The combination with a creaser arm, 75 of a feller having wings for guiding material to be folded, one of said wings having two guiding surfaces, one surface being capable of guiding material through the feller, and the other surface being capable 80 of coöoperating with said creaser arm for folding material for forming artificial lap seams.

4. The combination with a feller for forming a real lap seam, a feller member 85 connected thereto, means coöperating with said feller member for forming an artificial lap seam, and a stitching unit common to both the feller and feller member, whereby both the feller and feller member deliver 90 material to said unit.

5. The combination with a feller for forming a real lap seam, a feller member connected thereto, means coöperating with said feller member for forming an artificial 95 lap seam, said feller and feller member converging toward a common delivery point, and a stitching unit located in the path of delivery of and common to the feller and feller member.

6. The combination with means for folding material to form a real lap seam, of means for folding material to form an artificial lap seam, and stitching means common to and coöperating with both of said folding means for stitching material delivered from either of said folding means.

7. The combination with a frame, of a supporting member mounted therein having a slot, an arm pivotally mounted in said 110 slot, a stop on one side of said slot, and resilient locking means on the other side of said slot, whereby said arm may be locked in the desired position.

8. The combination with a frame, of a 115 supporting member mounted thereon and having a slot, a creaser arm pivotally mounted in said slot and having a bevel portion, a locking arm pivotally mounted upon said supporting member and having a cam, a flanged-plate mounted upon said supporting member, an arm connected therewith, and resilient means connecting said arm with said locking arm, the whole so arranged that the flanged-plate and the cam 120 coöperate to firmly hold the arm in its operative position.

In testimony whereof I affix my signature.

FRED H. McCOY.
